UNITED STATES PATENT OFFICE.

CHARLES S. CORNING, OF ROCKFORD, ILLINOIS, ASSIGNOR TO WARREN S. CORNING, OF CHICAGO, ILLINOIS.

METHOD AND APPARATUS FOR TREATING HYDROCARBONS.

Application filed September 8, 1923. Serial No. 661,662.

My invention relates to improvements in the method of treating hydro-carbons to produce gasoline, lubricating and other oils, and to an improved apparatus particularly adapted for carrying out the method described.

The invention has among its objects the production of a method and apparatus of the kind described that is exceedingly convenient, simple, efficient and satisfactory. It has particularly as an object a continuous method of treating heavy oil to secure lighter oils which will be particularly economical as well as rapid, and which will produce a uniform product. It has among its further objects the production of an apparatus of the kind described that is reliable, compact and self cleaning, and although compact, will have a considerable capacity and will at all times produce a uniform product with a minimum of loss.

In the present apparatus, the same is designed to liberate the lighter fuels in the form of vapors, which are then treated to a cracking process with the application of heat to further break up the resulting products. The apparatus, however, or such portions thereof as are applicable, may be used wherever found satisfactory, and in connection with such other apparatus as it may be found adapted.

Many other objects and advantages of the methods and construction herein shown and described will be obvious to those skilled in the art from the disclosures herein given.

To this end my invention consists in the novel methods, construction, arrangement and combination of parts herein shown and described, and more particularly pointed out in the claims.

In the drawings, wherein like reference characters indicate like or corresponding parts:

Fig. 1 is a plan view illustrating my improved apparatus;

Fig. 2 is a sectional view taken substantially on line 2—2 of Fig. 1;

Fig. 3 is a sectional view taken substantially on line 3—3 of Fig. 1; and

Fig. 4 is a sectional view taken substantially on line 4—4 of Fig. 3.

Referring to the drawings in which the

preferred embodiment of my invention is shown, I provide (see Fig. 2) one or more retorts of the desired size, shape and construction. I have illustrated three banks or series of retorts 1, 2, and 3, each bank consisting of one or more units preferably arranged in series, the several retorts in bank 1 being connected with the retorts in bank 2, and the retorts in bank 2 with the retorts in bank 3. There may be any number of banks and any number in the banks. As shown, these are arranged in a furnace or heating chamber 4, supplied with heat from the heating source 5, which may be in the form of an oil burner or any equivalent. The heat passing around the retorts as shown, is conducted through the chamber 6 to the stack 7, 8 being a heating or cracking chamber in communication with the chamber 6 and stack 7, as will be hereinafter described.

A description of one of the retorts in one of the banks will suffice for all as they are all substantially similar.

Referring particularly to Figs. 3 and 4, the furnace is provided with the walls 10 and top 14, enclosing the retorts which may be mounted upon the bases 11. Each retort is of the desired size and shape and formed with a chamber 12 as shown, and is of cast steel or any equivalent material, and may be provided with the flanges 13 which form a support for the top 14 of the furnace. Each retort is provided with a cover 15 which may be secured in place on the retort, if desired, in any suitable manner. Arranged in each retort is a partition or baffle 16 which may be secured in place and maintained in spaced relation with the sides of the chamber by bolts 17 or equivalent means. As shown, the partition plates are provided with passageways 19 at the bottom, and may, if desired, be slightly spaced from the side walls of the chamber as indicated at 18. They are also shown as spaced from the cover, as indicated at 20. Extending from each retort unit is a discharge pipe 22 which I prefer to connect with a header 23. Each of the banks of retorts are constructed substantially as just described in the preferred construction.

Referring to Fig. 1, 24 represents an intake pipe and 25 connecting pipes between

the several units, 26 being the discharge pipe connecting bank 1 with bank 2. As shown, feed pipe 24 communicates with the source of crude oil supply 27, a circulation being maintained, when required, by means of gravity or a pump 28 or the equivalent located as desired, driven by a motor 29 or equivalent means. Bank 2 is connected with bank 3 by means of pipe 30, 31 being a discharge pipe communicating with discharge pipe 33. If desired, and in some cases it is preferred, a pump 32 or the like may be provided in the discharge line 31, or at some other desired point, the same being operated by a motor 29 or the equivalent. Generally, I prefer to provide pyrometers 34 for ascertaining the temperature of the contents of the retorts.

As most clearly shown in Figs. 1 and 2, discharge pipes 35, 36 and 37 extend from the several headers through chamber 8, and are connected with a header 38 communicating with a discharge conduit or pipe 39. A valve 40, however, is preferably provided. I also prefer to provide the discharge pipes 41, 42, and 43 connected with the pipes 37, 36 and 35 respectively, and provide valves 44 and 45 for each pipe. Chamber 8 is provided with communicating passages with the chamber 6, the admission of heated gases from chamber 8 into chamber 6 being controlled by closures 48 or their equivalents, which I prefer to control thermostatically so that a desired temperature in chamber 8 may be maintained. As shown, 50 diagrammatically represents thermostats of suitable type. When the heated gases pass into chamber 8, they may pass through the chamber and out port 51 into the stack 7. The heated gases from the furnace may thus pass either through chamber 6 directly into the stack 7 or into chamber 8 to the stack 7 so as to maintain at a desired temperature the contents of the several pipes or conduits in chamber 8.

The operation of my improved device may be briefly described as follows:

The crude oil or the like is discharged into the first bank of retorts from the pipe 24 and circulates therein and out through pipe 26 to the bank 2, and similarly to bank 3, and thence out through the discharge pipe 31. As it passes into the bank 1, it is initially heated, and the more volatile gases are liberated and pass up into the header, and thence through the pipe 35 into the chamber 8. It will be noted that owing to the particular construction of retort, the circulating crude oil is spread out into a thin stream, and due to the partition plate travels down and up, and a considerable area exposed to heated surfaces so that the same very quickly is heated to a point to liberate the gases that are easily volatile. Continued

circulation liberates the gases in the banks 2 65 and 3, etc., depending upon the number of banks. By providing the pyrometers 34, it is possible to know the temperature of the circulating fluid, and it will be noted that these temperatures may be positively controlled. I also preferably provide the pyrometers 34' or their equivalents. In the first place, the heat in the furnace may be regulated, and if an oil burner is provided, may be controlled to a very close degree. 70 By controlling the pump 28, the circulation or rate of circulation may be positively controlled. This is also the case where the additional pump 32 is provided. By increasing the flow or decreasing the same, an even 75 temperature may be maintained. It may be mentioned that this positive control is very desirable as it is my object to liberate the gases or more volatile constituents of the crude oil without any appreciable amount 80 of cracking, it being desirable to crack the gases as they pass through the chamber 8. I prefer to crack as little as possible in the retorts and to crack as much as possible in the cracking pipes in the chamber 8. A 85 pump 32 is particularly desirable where the crude oil passing through the retorts becomes somewhat heavy or sluggish in the last bank. The gases passing through pipes 35, 36 and 37 in chamber 8 are further heat- 90 ed, and it is preferably at this point that the cracking, as it is termed, takes place, the same passing into the header 38 and through pipe 39 to where desired for further treatment. Generally they are passed out and 95 condensed, distilled, or otherwise treated. It may be mentioned that a small degree of vacuum may be maintained in the header 38 or conduit 39 so as to induce a slight circulation or movement, which may be varied to vary the results. By providing the pipes 41, 42, and 43, and the several valves mentioned, it is possible to direct all gases from the apparatus from the several retorts independently. In other words, the gases 100 may be drawn off in such manner as may be found desirable, either into the header or through the separate lines or in various combinations.

I have shown (see Fig. 1) drawoff pipes 115 46 which may be installed if desired, and which are sometimes desirable in the manufacture of lubricating oils as in this case the fluid in the retort may be withdrawn at a desired point in the treatment for such other treatment as is desired. It should be particularly noted that the retort itself may be used wherever found applicable for the heating and vaporizing of fluids, its use not being limited to oil treating apparatus 120 125 exclusively.

Having thus described my invention, it is obvious that various immaterial modifica-

tions may be made in the same without departing from the spirit of my invention; hence I do not wish to be understood as limiting myself to the exact form, construction, arrangement and combination of parts herein shown and described or uses mentioned.

What I claim as new and desire to secure by Letters Patent is:

1. The method of manufacture of oils with a low boiling point from a higher boiling mixture of hydrocarbon oils containing low boiling hydrocarbons consisting in conducting said mixture in a stream of considerably greater width than thickness and applying heat thereto so as to vaporize and separate therefrom the low boiling point oils with a minimum amount of cracking, separately withdrawing different portions of the vapors from the residue at different stages of the treatment thereof, and thereafter cracking the vapors separately by heating the same in cracking zones.

2. The method of treating hydro-carbon oils consisting in flowing a higher boiling liquid hydro-carbon mixture containing low boiling hydro-carbons over a series of heated surfaces so as to produce vapors of low boiling point and separately withdrawing different fractions of vapors of low boiling point from the residue at a succession of points, thence cracking the vapors separately by heating same in the cracking zones and thence withdrawing the cracked vapors from the cracking zones and immediately blending them.

3. In an oil refining system, a furnace, a plurality of retorts in said furnace, means for passing oil in thin sheets continuously through said retorts, means for separately withdrawing vapors from above said retorts, a plurality of independent means for cracking the vapors whereby the vapors from each of said retorts is treated independently of the vapors of the other retorts and means for withdrawing the independent cracked vapors from said last means and immediately blending them.

4. In an oil refining system, a furnace, a plurality of retorts in said furnace, said retorts being spaced apart lengthwise thereof, means for passing oil through adjacent retorts, means for withdrawing vapors from above said retorts, means for withdrawing the oil from said retorts, means for cracking the vapors whereby the vapors from each of said retorts is treated independently of the vapors from the other retorts and means for withdrawing the independent cracked vapors from the last-mentioned means and immediately blending them.

5. In an oil refining system, a furnace, a plurality of banks of retorts spaced therealong from the front toward the rear thereof, each of said banks having an adjacent bank of retorts communicating with it, a

separate offtake pipe connected to the retorts of each bank for drawing the vapors therefrom, conduits connecting adjacent banks for passing the oil through adjacent banks, means for causing the oil to flow through said retorts, means associated with each bank for cracking the vapors withdrawn therefrom and means whereby to immediately blend the cracked vapors.

6. In an oil refining system, a furnace, a plurality of banks of retorts spaced therein, means for conducting the oil continuously from the rear bank of retorts to the front bank and for withdrawing the oil from the front bank of retorts, individual offtake pipes for each bank of retorts for withdrawing the vapors from thereabove, a common offtake communicating with all of said individual offtakes, and means for controlling the flow of vapors through said individual and common offtakes.

7. In an oil refining system, a furnace having a combustion chamber, a plurality of retorts therein, conduits connecting said retorts, offtake pipes for said retorts, a chamber above the combustion chamber at the rear of the furnace for enclosing said offtake pipes, and thermostatically controlled dampers between said chambers for controlling the admission of the heating medium to said top chamber.

8. In a refining system, a furnace, a plurality of banks of retorts arranged in said furnace, means for conducting the oil continuously through said retorts, offtake pipes connected to the top of said retorts for withdrawing the vapors therefrom, a partition in each retort closely adjacent the opposed side walls of the retort so as to form wide shallow chambers in each retort, whereby the oil travels through each retort substantially in a sheet and means communicating with each offtake pipe for cracking the vapors.

9. In an oil refining system, a furnace, a retort therein comprising a casing of relatively large area, a partition within said casing between its opposed side walls to form a pair of chambers therewith communicating with each other at the bottom, an inlet to one chamber adjacent the upper end, an outlet from the other chamber adjacent the upper end, whereby the oil passes through the pair of chambers in the form of a thin sheet, said inlet and outlet being arranged above the furnace, and an offtake pipe above said inlet and outlet for withdrawing the vapors therefrom.

10. In an oil refining system, a furnace, a separate chamber at the rear thereof and arranged thereabove, a stack leading from the rear of the furnace, a port through said stack communicating with the upper chamber, doors between said upper chamber and furnace, a series of banks of retorts in said

furnace between said upper chamber and the front of the furnace, the tops of said retorts projecting above the top of the furnace, means arranged above the furnace for 5 conducting oil through all of said retorts in succession, individual offtakes communicating with each bank of retorts above said oil conducting means so as to withdraw the vapors therefrom, said offtakes extending 10 rearwardly within said upper chamber, a common offtake communicating with the individual offtakes, valve means for controlling the flow through said individual offtakes and through said common offtake, 15 thermostatically controlled means for operating the doors between the combustion chamber and the offtake enclosing chamber, and means for ascertaining the temperature at all times in each bank of retorts.

20 11. In an oil refining system, a furnace, a plurality of banks of retorts spaced therein, means for conducting the oil continuously through the retorts and for withdrawing the oil from the retorts, individual offtake pipes 25 for each bank of retorts for withdrawing the vapors therefrom and a common offtake communicating with all of said individual

offtakes, and means for controlling the flow of vapors through said individual and common offtakes. 30

12. In an oil refining system, a furnace, a plurality of banks of retorts spaced therein, means for conducting the oil continuously through the retorts and for withdrawing the oil from the retorts, individual offtake pipes for each bank of retorts for withdrawing the vapors therefrom and a common offtake communicating with all of said individual offtakes, means for controlling the flow of vapors through said individual and common offtakes, and means associated with each individual offtake for cracking vapors passed through said offtake. 35 40

13. In an oil refining system, a furnace having a combustion chamber, a retort therein, an offtake pipe for said retort, a second chamber opening into the combustion chamber and enclosing said offtake pipe, and thermostatically controlled means for controlling the admission of the heating medium to said second chamber. 45 50

In testimony whereof, I have hereunto signed my name.

CHARLES S. CORNING.
